UNITED STATES PATENT OFFICE.

EPPA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

SUPPORT FOR WEFT-DETECTING MECHANISM.

Original application filed October 20, 1921, Serial No. 509,113. Divided and this application filed October 13, 1924. Serial No. 743,190.

This application is a division of my prior application on weft detecting mechanism, Serial No. 509,113, filed Oct. 20, 1921, manufacturing as Patent No. 1,514,934 dated November 11, 1924, and relates particularly to the means therein shown for supporting the detecting mechanism on the loom frame.

It is the object of my present invention to provide novel devices for supporting the weft detecting mechanism and for adjusting said mechanism in several different directions relative to the shuttle and weft carrier.

A preferred form of my invention is shown in the drawings in which

Fig. 1 is a rear elevation of parts of the loom containing my improved weft detecting mechanism mounted thereon;

Fig. 2 is a sectional side elevation, taken along the line 2—2 in Fig. 1; and

Figs. 3 and 4 are end and side elevations of the eccentric stud.

Referring particularly to Figs. 1 and 2, I have shown a portion of a loom side 10 to which is bolted a bracket 11. A block 12 is secured to the bracket 11 by bolts 13 extending through a slot in the block and permitting forward and rearward adjustment thereof. The block 12 has a rearwardly inclined depending arm 14 having a bearing for the cylindrical portion 15 of an eccentric adjusting stud 16 (Fig. 4). The stud is held in adjusted angular position in its bearing by a binding nut 17 threaded to the end of the stud.

At its lower end the arm 14 is also provided with depending projections 19 and 20 (Fig. 2) in which adjusting screws 21 and 22 are threaded. A frame or support 23 is provided with a split bearing fitting the eccentric portion of the stud 16 and the support may be clamped thereon by a binding screw 24. A lug or projection 25 extends laterally from the support 23 and is engaged on its opposite sides by the adjusting screws 21 and 22 (Fig. 2) previously described.

The angular position of the support 23 upon the eccentric stud 16 may thus be adjusted as desired, and the stud itself may also be turned to change the vertical or lateral position of the support, the stud being provided with a suitable screw driver slot for such adjustment. The support 23 pro-

vides guides 26 and 27 for a vertically movable transerrer actuating member 28 which is periodically reciprocated by suitable connections to the loom cam shaft (not shown).

The transerrer and its actuating mechanism form no part of my present invention and for further details, reference is made to my prior application Serial No. 470,335, filed May 17, 1921.

A stand 31 is yieldingly secured to the upper end of the support 23, the stand being provided with a groove adapted to receive a transversely extending rib or projection 32 on the front face of the support 23. The stand is held in yielding engagement with the rib and the front face of the support by a bolt 33 extending freely through the parts 23 and 31 and having a compression spring, not shown, inserted between its head and the rear face of the support.

The stand 31 has a rearwardly extending portion 35 which is grooved or slotted to receive a plurality of slidable detecting plungers 36. A cover or cap 37 (Fig. 9) is slidably mounted on the stand 31 and prevents displacement of the plungers.

For a full description of the construction and operation of the weft detecting mechanism itself reference is made to my prior Patent No. 1,514,934, of which this is a division application.

The advantages of my improved support are readily understood and very important.

By a combination of the several adjustments described, the weft detector may be securely held in any desired position relative to the shuttle and weft carrier, the parts being raised or lowered and being moved forward or back by adjusting the eccentric stud 16, being adjusted angularly by the screws 21 and 22, and being also adjustable longitudinally of the weft carrier along the eccentric stud 16.

The weft detector may thus be easily adjusted to cooperate with any desired shuttle or weft carrier and the adjustment may be made with a minimum expenditure of time and labor.

Having thus described my invention, it will be evident that changes and modifications may be made therein by those skilled in the art within the spirit and scope of my invention as set forth in the claims, and I

do not wish to be otherwise limited to the details herein disclosed, but what I claim is:—

1. In a weft replenishing loom having a loom frame, weft detecting mechanism, a support therefor, an eccentric stud on which said support is mounted, and means to secure said mechanism and said stud in adjusted position, said stud being angularly adjustable in said frame, and said support being both angularly and longitudinally adjustable on said stud.
2. In a weft replenishing loom having a loom frame, in combination, weft detecting mechanism, a support therefor having a horizontally disposed cylindrical opening therein, a stud fitting freely in the opening in said support and having an eccentric projection seated in an opening in said frame, means to clamp said support to said stud, and means to secure said stud in angular adjusted position in said frame.
3. In a weft replenishing loom having a loom frame, in combination, weft detecting mechanism, a support therefor having a

horizontally disposed cylindrical opening therein, a stud fitting freely in the opening in said support and having an eccentric projection seated in an opening in said frame, said stud being angularly adjustable in said frame, means to adjust said support angularly on said stud, and means to secure said support to said stud and to secure said stud to said frame.

4. In a weft replenishing loom having a loom frame, in combination, weft detecting mechanism, a support therefor, having a horizontally disposed cylindrical opening therein, a stud mounted on said frame and freely fitting the opening in said support, said frame having spaced depending projections and said support having an arm disposed between said projections, and adjusting screws threaded in said projections and engaging said arm to adjust said support angularly on said stud.

In testimony whereof I have hereunto affixed my signature,

EPPA H. RYON.
